UNITED STATES PATENT OFFICE.

JOHN H. HAWLEY, OF NEW YORK, N. Y.

DESIGN FOR A BUTTON.

45,992.

Specification for Design.

Patented June 23, 1914.

Application filed March 31, 1914. Serial No. 828,634. Term of patent 3½ years.

To all whom it may concern:

Be it known that I, JOHN H. HAWLEY, a citizen of the United States, and a resident of the borough of Manhattan, city and State of New York, have invented a new, original, and ornamental Design for Buttons, of which the following is a specification.

My design is represented in the accompanying drawing in which:

Figure 1 is a plan view. Fig. 2 is a side view. Fig. 3 is a section on line 3—3 of Fig. 2, of a button illustrating my new design.

The design consists of the ornamental shape shown. A substantially cylindrical cavity is provided in the central portion thereof. The bottom and sides of the cavity, and the outside surface of the button, are

decorated with relatively light and relatively dark substantially vertical stippled areas of varying widths, the contrasting colors of the respective areas blending with one another.

I claim:

The ornamental design for a button as shown and described, or any colorable imitation thereof.

In testimony that I claim the foregoing as my own, I have hereto affixed my signature in the presence of two witnesses.

JOHN H. HAWLEY.

Witnesses:

JOHN J. RANAGAN,
AGNES C. O'CONNELL.
